UNITED STATES PATENT OFFICE.

OSCAR WILLIAMS AND ELBERT C. BAKER, OF SULLIVAN, INDIANA.

ACETYLENE-GENERATING LAMP.

1,132,894.

Specification of Letters Patent. Patented Mar. 23, 1915.

Application filed July 29, 1914. Serial No. 853,865.

To all whom it may concern:

Be it known that we, OSCAR WILLIAMS and ELBERT C. BAKER, citizens of the United States, residing at Sullivan, in the county of Sullivan and State of Indiana, have invented certain new and useful Improvements in Acetylene-Generating Lamps, of which the following is a specification.

The acetylene generating lamp which is the subject matter of the present application for patent is designed more particularly for the use of miners and others working underground, and its object is to provide a lamp of novel construction which permits renewal of the carbide container without the flame being extinguished. This object is attained by means of a combination and arrangement of parts to be hereinafter described and claimed, reference being had to the accompanying drawing, in which—

Figure 1 is a central vertical section of the lamp, and Fig. 2 is a similar view showing a slightly modified water-feed valve structure.

Referring specifically to the drawings, the lamp is composed of three parts, to wit: a carbide container 10, a cap 11 for said container, and a water receptacle 12. These three parts are separately connected. The carbide container forms the base of the lamp and has a threaded neck 13 on which the cap is screwed. In the top of the cap is a depression 14 which is screw-threaded and into which screws the reduced bottom portion 15 of the water receptacle. Any other connection permitting separation of the carbide container, the cap and the water receptacle may be provided. The cap has a bottom flange 16 between which flange and the top of the carbide receptacle is interposed a gasket 17. The carbide container may be filled upon removal of the cap. The carbide container 10 and the cap 11 are in open communication, and the latter is fitted with a burner nipple 18 provided with a tip 19. Between the bottom of the part 15 and the opposite portion of the wall forming the depression 14 is interposed a gasket or washer 20. From the center of the depressed portion 14 of the cap 11 depends a tube 21 which opens into the depression and has a seat at its lower end for a valve 22, said seat and valve being located in the carbide container 10. The valve is provided with a closing spring 23 located in the tube 21 between the valve seat and an abutment 24 on

the upper end of a stem 25 passing through the tube and carrying the valve. The top of the water receptacle 12 has a boss 26 the center of which is internally threaded to receive a screw-plug 27 having a milled finger-piece 28 to facilitate its manipulation. The screw-plug carries a depending stem 29 which extends downward through the water receptacle and through a central opening 30 in the bottom of the reduced portion 15 of said receptacle. The lower end of the stem has an enlarged conical portion 31 serving as a valve plug and designed to close the opening 30. The stem is in line with the valve stem 25 and is designed to engage the upper end thereof to unseat the valve 22.

In operation, the carbide container 10 and the water receptacle 12 being filled, said parts and the cap 11 are connected as described, and shown in Fig. 2. The plug 27 is now operated to bring the stem 29 down against the upper end of the valve stem 25, and upon continuing to screw the plug down the valve 22 is unseated, and the valve plug 31 is also carried out of the opening 30. Water from the receptacle 12 is now free to pass from the same through the opening 30 and down the tube 21, and thence into the carbide container 10. The water feed is readily regulated by operating the plug 27 to open or close the valve 22 more or less. The receptacle 12 has a filling nipple 32 closed by a vented cap 33. Whenever it becomes necessary to replenish the carbide supply, an extra container 10 carried by the miner will be applied to the lamp after removal of the empty container. This can be done without leaving the miner in the dark. The water receptacle 12 will be removed leaving the container 10 with the cap 11 in place thereon. Upon removing the water receptacle, the stem 29 releases the valve stem 25, and the valve 22 then closes to prevent escape of gas. The small volume of gas remaining in the container keeps the lamp burning until another container with a cap 11 and a fresh supply of carbide is applied to the water receptacle, and upon applying this container, the valve 22 of said container is opened as before, whereupon the generation of gas is resumed. In order to guard against the accidental turning of the plug 27, the top of the water receptacle, in front of the plug, has a raised portion 34 which prevents the plug from striking against an obstacle as the miner moves

about, and thus disturbing the adjustment of the water feed.

Fig. 2 shows a slightly modified structure. Here the water receptacle 12 seats squarely 5 on top of the cap 11 and has a depending central nipple 35 at the bottom which is threaded to screw into the upper end of a tube 36 opening through the top of the cap 11 and depending into the carbide 10 tainer 10. The lower end of the tube has a seat for a water feed valve 37 provided with a closing spring 38 which is located on the outside of the tube. The valve has a stem 39 extending upward in the tube and 15 engageable by the lower end of a stem 40 similar to the stem 29 hereinbefore described. The stem 40 also has a valve 41 which seats in the nipple 35, and said stem is operated by a screw-plug 27 as before.

20 The modified form of lamp operates in the same manner as the one first described.

We claim:

1. In an acetylene generating lamp, a carbide 25 container, a cap mounted on said container and provided with a burner nipple, and a water receptacle removably connected to the cap.

2. In an acetylene generating lamp, a carbide 30 container, a cap mounted on said container and provided with a burner nipple, a water receptacle removably connected to the cap, a water-feed valve carried by the cap, and means for operating said valve carried by the water receptacle, said valve and 35 its operating means being separable.

3. In an acetylene generating lamp, a carbide 40 container, a cap mounted on said container and provided with a burner nipple, a water receptacle removably connected to the cap and having an outlet, a water-feed valve carried by the cap, means for operating said valve carried by the water receptacle, said valve and its operating means being separable, and means carried by the valve operating 45 means for controlling the outlet of the water receptacle.

4. In an acetylene generating lamp, a car-

bid container, a cap mounted on said container and provided with a burner nipple, a water receptacle removably connected to 50 the cap, a water-feed tube depending from the cap into the carbide container and having a valve seat in said container, a valve for said seat, a stem extending from the valve, said stem being located in the aforesaid 55 tube, a closing spring for the valve, and a longitudinally adjustable stem carried by the water receptacle and engageable with the aforesaid valve stem to open the valve.

5. In an acetylene generating lamp, a carbide 60 container, a cap mounted on said container and provided with a burner nipple, a water receptacle removably connected to the cap, a water-feed tube depending from the cap into the carbide container and having 65 a valve seat in said container, a valve for said seat, a stem extending from the valve, said stem being located in the aforesaid tube, and a longitudinally adjustable stem carried by the water receptacle and engageable 70 with the aforesaid valve stem to operate the valve.

6. In an acetylene generating lamp, a carbide 75 container, a cap mounted on said container and provided with a burner nipple, a water receptacle removably connected to the cap having an outlet, a water-feed tube depending from the cap into the carbide container and having a valve seat in said 80 container, a valve for said seat, a stem extending from the valve, said stem being located in the aforesaid tube, a longitudinally adjustable stem carried by the water receptacle and engageable with the aforesaid valve stem to operate 85 the valve, and means carried by said adjustable stem for controlling the outlet of the water receptacle.

In testimony whereof we affix our signatures in presence of two witnesses.

OSCAR WILLIAMS.
ELBERT C. BAKER.
